UNITED STATES PATENT OFFICE

109,128

DESIGN FOR A BIRD FEEDING STATION AND OPEN-FACED BIRD HOUSE

Lloyd G. Copeman, Flint, Mich.

Application July 14, 1937, Serial No. 70,448

Term of patent 14 years

To all whom it may concern:

Be it known that I, Lloyd G. Copeman, a citizen of the United States of America and residing at Flint, in the county of Genesee and State of Michigan, have invented a new, original, and ornamental Design for a Bird Feeding Station and Open-Faced Bird House, of which the following is a specification, reference being made to the accompanying drawing, forming part thereof.

The figure is a perspective view of a bird feeding station and open faced bird house showing my new design.

I claim:

The ornamental design for a bird feeding station and open-faced bird house substantially as shown.

LLOYD G. COPEMAN.
